UNITED STATES PATENT OFFICE.

ERASTUS G. OAKLEY, OF SOUTHPORT, CONNECTICUT, ASSIGNOR TO BRIDGEPORT BRASS COMPANY, OF BRIDGEPORT, CONNECTICUT.

METHOD OF MAKING BATTERY NUTS.

Application filed April 28, 1922. Serial No. 557,111.

This invention relates to battery or other nuts adapted to be used in connection with binding posts or terminal posts in making electrical connections. While my invention primarily concerns the method of manufacture of articles of this character, I also contemplate the provision of a battery or binding post nut of improved form.

One object of my invention is the provision of a nut which is cheap and economical to manufacture and yet very serviceable.

Another object of my invention is the provision of a new and improved method of manufacture of articles of the kind mentioned.

Still another object of my invention is to provide a method of manufacture of battery nuts or similar articles from wire stock wherein the waste of material will be reduced to a minimum and by which the finished article may therefore be produced at a low cost.

To these and other ends, the invention consists in the novel features and combinations of parts to be hereinafter described and claimed.

In the accompanying drawings:

Fig. 1 is a side elevational view of a battery nut made in accordance with the principles of my invention;

Fig. 2 is a sectional view of the same;

Fig. 3 is a view showing the article as it appears in various stages of its manufacture;

Fig. 4 is a fragmentary view of the heading press used in connection with one step in the method of manufacture of the nut;

Fig. 5 is a view similar to Fig. 4, showing the parts in a different position, wherein the second step in the heading operation is performed;

Fig. 6 is a view showing the drilling operation;

Fig. 7 is a view partly in side elevation and partly in section, showing the manner in which the flange is formed at the lower end of the nut; and

Fig. 8 is a view similar to Fig. 6, but showing the operation by which the bore is tapped.

While for the purpose of disclosing my invention fully and clearly I have illustrated a preferred form of battery nut and one method by which it may be made, it will be understood that I do not limit myself

to the precise shape or structure of the article shown, nor do I limit myself to the exact steps herein set forth in the manufacture of the article, nor to the sequence in which these steps are preferably performed. It will also be clear that each of the so-called steps in the manufacture of the nut may be the result of a fewer or greater number of operations than those described, without departing from the principles of the invention.

In Figs. 1 and 2 of the drawings, I have shown a preferred form of battery nut consisting of body portion 10 having a knurled head 11 at the upper portion thereof and a lower flanged portion 12. The flanged portion 12 has a lateral face or edge 13, which is substantially parallel with the axis of the threaded bore 14 of the nut. The bore 14 below the threads thereof is flared out, as at 15, in conformance with the external flared flange 12. It will be apparent that this flared or bell shaped portion of the nut will operate to seat the nut effectively upon the electric wire looped about the binding post, affording an extended skirt-like bearing thereon.

While the manufacture of my improved battery nut may be effected in other ways, I prefer to use the method herein described in which the nut is manufactured from a piece of brass generally cylindrical in shape, as shown at 16, in Fig. 3. This blank may readily be provided by cutting a piece of proper length from a wire or rod of suitable diameter. In general, the operations by which the battery nut is produced from the blank consist of: a heading operation, the result of which is the headed blank, shown at 17; a drilling and beveling operation, the product of which is shown at 18; a flaring operation, wherein the blank is formed, as shown at 20; and lastly, the tapping of the bore to produce the finished article shown in Figs. 1 and 2. These operations will now be described in greater detail.

The heading operation may be the result of one or more separate steps, and in the form shown is preferably accomplished in two steps or operations, which may be performed in a double stroke header provided with a single die. The die, as illustrated at 21, is provided with a die opening 22 of proper shape, the periphery of the upper part of this opening being suitably ribbed,

as at 23, to form ribs or knurlings upon the head of the nut. Within the die opening there may be provided a stripping and centering punch 24 having a conically shaped end 25, which impresses the blank to center the drill used in a future operation. The first step of the heading operation is that of subjecting the blank to the stroke of the punch 26 by which it is formed into the shape shown at 27 in Fig. 4.

Upon the second stroke of the header the punch 28 is brought down upon the blank, as shown at Fig. 5, and the heading operation is completed. The metal of the blank is caused to flow out into the enlarged upper portion of the die opening 22 and the peripheral ribs impress complementary ribs or knurled portions upon the periphery of the head.

20 The blank which is now in the form shown at 17, in Fig. 3, is then fed into a drilling machine shown, in a fragmentary way, in Fig. 6. The clamp 29 is preferably arranged to hold two of the blanks in such a manner that 25 both may be simultaneously drilled from opposite sides of the clamp. As the two blanks 17 are securely held in the clamp, the drills 30 enter from either side thereof and drill out the bores 31 in the blanks. The drills 30 are preferably mounted in hollow mills 32, provided with cutting surfaces 33 arranged to bevel the unheaded end of the blank, as shown at 34. It will be noted that 35 while the drilling and beveling operations may be performed independently of each other, I prefer to perform them simultaneously, as has just been described.

The blank which is now in the form shown at 18, in Fig. 3, is then placed in a suitable 40 dial press and by the action of a properly shaped punch the beveled end is flared over to provide the flange 12, the beveled portion 34 becoming the edge 13 of the finished product. The drill press may comprise an 45 anvil 35 over which is mounted a rotatable dial 36, provided with a plurality of openings, one of which is shown at 37. Within the opening 37 is mounted a sleeve or collar 38, within which the blank 18 is placed. 50 The punch 39 is then brought down, the small end 40 entering the bore of the blank to some extent and the unheaded end thereof is flared out, as shown at 20, in Figs. 7 and 3.

For the production of the finished article, it is now only necessary that the bore 31 be tapped or threaded, and this operation is performed in a tapping machine, shown in a fragmentary way in Fig. 8. Two of the blanks are placed in opposite sides of a 55 clamp 41 and are threaded simultaneously by the taps 42 arranged to enter from opposite sides. The finished product, shown in Figs. 1 and 2, is then removed from the tapping machine.

60 It will be obvious that by my method a

battery nut of improved texture and form is produced with very little loss of material, which results in a considerable economy in the manufacture of such articles. The metal of the blank is condensed and the article is strengthened by the described working of the metal, and only a small amount of scrap is produced. Moreover, the method may be carried out by simple and relatively inexpensive automatic machine operations, and the finished article may be produced from the blank by a relatively small number of these operations.

What I claim is:

1. The method of making a battery nut 80 or the like, which consists of heading one end of a cylindrical piece of stock, drilling a hole through the same, flaring out the other end, and tapping the drilled hole.

2. The method of making a battery nut 85 or the like which comprises heading one end of a piece of solid stock, drilling through the same, beveling the unheaded end and flaring out the metal of the last named end, substantially as described.

90 3. The method of making a battery nut which comprises preparing a blank having a cylindrical body portion and bore therethrough, and a head upon one end thereof, beveling the unheaded end of the blank and then flaring out the beveled end so that the beveled portion becomes a lateral edge of the flared flange.

95 4. The method of making a battery nut or the like, which includes beveling one end 100 of a piece of stock and punching or flaring out the end thereof so that the beveled portion becomes a lateral edge of the flared flange.

105 5. The method of making battery nuts 105 or the like, which comprises heading and drilling through a given length of stock, beveling the unheaded end thereof and flaring out this end so that the beveled face assumes a position substantially parallel to 110 the axis of the drilled bore.

115 6. The method of making a battery nut which comprises preparing a blank having a cylindrical body portion and a head on one end thereof, perfecting a bore therethrough, and then flaring out the unheaded end of the blank to form a flared mouth leading into the bore while maintaining the exterior diameter of the blank at the intermediate portion thereof.

120 7. The method of making battery nuts or the like which includes drilling a bore through a piece of stock, beveling one end thereof outwardly from the bore and then flaring out the beveled end to form a laterally projecting flange.

125 8. The method of making battery nuts or the like, which comprises heading one end of a suitable length of solid stock, drilling a hole through the same and flaring outwardly 130

the wall of the resulting tubular blank at the end opposite the head to form a bell shaped mouth leading into the bore.

9. The method of making battery nuts or
5 the like, which comprises heading and knurling one end of a suitable length of solid stock having a cross-section substantially equal in size to the body portion of the finished nut, drilling a hole through the same, flaring out
10 the wall at the unheaded end of the blank and tapping the drilled hole.
10. The method of making battery nuts or
the like, which comprises heading one end of a suitable length of solid stock of circular
15 cross-section, drilling a hole through the headed blank, beveling the unheaded end

of the blank, flaring the beveled end outwardly so that the beveled portion becomes a lateral edge of the flared flange, and tapping the drilled bore. 20

11. The method of making a battery nut, which comprises forming an opening through a solid blank and operating on opposite ends of the blank to form a head upon one end and a flared mouth portion at the other end, 25 while maintaining the exterior diameter of the blank at the intermediate portion thereof.

In witness whereof, I have hereunto set my hand on the 25th day of April, 1922.

ERASTUS G. OAKLEY.
